BACON COOKER

Richard F. Saurer, Lexington, Ohio, assignor to Westinghouse Electric Corporation

Filed Apr. 16, 1970, Ser. No. 22,467

Term of patent 14 years

Int. Cl. D7—04

U.S. Cl. D81—10

FIG. 1 is a front isometric view of a bacon cooker embodying my new design; and

FIG. 2 is a rear isometric view thereof.

I claim:

The ornamental design for a bacon cooker, substantially as shown.
